UNITED STATES PATENT OFFICE.

THOMAS R. GIBSON, OF FREMONT, NEBRASKA.

POWER MECHANISM.

SPECIFICATION forming part of Letters Patent No. 259,127, dated June 6, 1882.

Application filed April 13, 1882. (No model.)

To all whom it may concern:

Be it known that I, THOMAS R. GIBSON, of Fremont, Dodge county, Nebraska, have invented a new and useful Improvement in Power Mechanism, of which the following is a full, clear, and exact description.

My invention relates to mechanism in which a train of wheels is driven by a weight; and it consists in the combination therewith of a governing device having the object to obtain steady and uniform power for use in pumping water, grinding grain, and for other purposes where a limited power is required. The construction and operation are set forth hereinafter.

Reference is to be had to the accompanying drawings, forming part of this specification, in which similar letters of reference indicate corresponding parts in all the figures.

Figure 1 is a side elevation of the improved mechanism, and Fig. 2 is a plan view of the same.

Upon a suitable frame, A, is a train of gear-wheels, B C D E F G, on shafts a, b, c, and d. On shaft a of the primary wheel B is a drum, e, to which is connected a rope, f, that passes over a pulley and carries a weight, g, on its end. The weight may be of any suitable character, and by its descent serves to drive the gearing and revolve the shaft d at the end of the train, from which the power is to be taken. h is a drum on shaft c, provided with a rope, i, that is for use in winding up the rope f and raising the weight g, horse or other power being used for that purpose.

H is a governor of the centrifugal type, the stem k of which is connected to the outer end of a lever, l, that is hung on a fixed support. The lever l is placed above a brake-wheel, m, fixed on the shaft c, so as to bear on the rim of the wheel when brought down by the rise

of the governor-balls. The governor is operated by a belt, n, from a pulley, o, on shaft d, and lever l is balanced by a weight, p, attached on its outer end.

In operation, the weight being raised, the 45 train of gearing is set in motion, and the brake-lever bearing with more or less pressure on the wheel m the speed of shaft d is kept uniform. Increase of speed acts to raise the governor-balls and increase the pressure of the 50 brake-lever upon the wheel m, while, on the other hand, if the speed is checked and falls below the normal point the reverse action takes place.

I do not limit myself to any size, number, or 55 special arrangement of the wheels of train, as those details may be varied without departing from my invention.

The winding-drum h is to be provided with clutch or ratchet connections in such manner 60 that it may be turned backward for winding the weight without turning the power-shaft d backward. Springs may be substituted for the driving-weight, if desired.

The brake-wheel m may be attached upon 65 either shaft of the train of wheels.

Having thus described my invention, I claim as new and desire to secure by Letters Patent—

The combination, with two drums, e h, connected by intermediate mechanism, and adapted to be operated in opposite directions alternately by power and a weight, of the brake-wheel m and lever l, the latter connected at the outer end with the stem k of a governor, H, as and for the purpose specified.

THOMAS R. GIBSON.
